UNITED STATES PATENT OFFICE.

WILLIAM G. HETTICH, OF CHICAGO, ILLINOIS, ASSIGNOR TO STANDARD X-RAY COMPANY, OF CHICAGO, ILLINOIS, A CORPORATION OF ILLINOIS.

RECTIFIER.

Application filed January 30, 1926. Serial No. 84,958.

My invention relates to a rectifier of antioned at 90° intervals are a plurality of 5 alternating electric current and particularly to a mechanical rectifier. One object of my invention is the provision of a rectifier in which the energy loss due to the resistance of the air at the spark gap is reduced to a minimum. Another object is the provision of means for immobilizing or holding the air ionized by the electric discharge or 10 current passage across the gap. Another object is the provision of means for minimizing the effect of the windage of the rotating parts in increasing resistance across the air gap. Other objects will appear from 15 time to time in the course of the specification and claims.

I illustrate my invention more or less diagrammatically in the accompanying drawings, wherein—

20 Figure 1 is a diagrammatic showing of my rectifier shown as employed with a Coolidge tube;

25 Figure 2 is a side elevation of the rotating parts and fixed contacts with parts in section;

Figure 3 is an enlarged section through one of the fixed contacts or brushes; and

Figure 4 is a plan view of the structure of Figure 3 with parts in section.

30 Like members are illustrated by like characters throughout the specification and drawings.

A is any suitable driving member, preferably a synchronous motor, revolving in 35 synchronism with the alternations of the alternating current employed. A¹ is any suitable shaft, preferably of bakelite or similar insulating material, adapted to be rotated by and in synchronism with the motor A.

40 Mounted on it is a disc A², preferably of bakelite or some other suitable insulating material. The supports and bearings for the rotating parts are not indicated since they form no part of the present invention.

45 Mounted about the periphery of the disc A² at any suitable interval, for example at 90° intervals, are the contacts or brushes A³ A⁴ mounted in pairs, each pair being connected for example by the metallic strip A⁵ A⁶ extending along the periphery of the disc.

50 The brushes are in the form of thin blades having arcuate outer surfaces preferably concentric with the axis of rotation of the disc.

55 Mounted about the disc A² and also posi-

fixed contacts or blades B, B¹, B² and B³. Each such blade is associated with or mounted in a hollow casing B⁴, the casing having an open mouth B⁵, in which the blade is set, 60 the mouth having at each side the inwardly projecting lips or walls B⁶ which may, if desired, project inwardly toward the disc, even to the point of overlapping the blades A³ A⁴. The hollow interior of each member 65 B⁴ preferably communicates with the outer air only through the mouth B⁵.

Whereas in practice I may wish to employ more than one disc, I have illustrated a rectifier in which but one disc is shown, and I 70 do not wish to be limited to any specific number of discs, or to any specific spacing of the brushes or contacts about the discs.

C generally indicates any suitable transformer which may include for example the 75 laminated iron core C¹, about one arm of which, C², is wound the primary coil C³. The primary coil C³ may be in circuit with any suitable auto transformer, generally denominated as D, the details of which form 80 no part of the present invention. D¹ D² represent the conductors of the alternating current circuit.

The opposite arm C⁴ of the core has wound about it the secondary coil C⁵. The 85 circuit may extend from the brush or blade B along the conductor E to the coil C⁵, thence along the conductor E¹ to the blade B², or the line within the casing E may be omitted, the casing B⁴ being formed of conductive material. From the blade B¹ the conductor E² may extend for example to the Coolidge tube generally denominated as G. From the opposite terminal of the Coolidge tube extends the conductor E³ to the fourth 95 blade B³. G¹ is any suitable conductor extending to the filament of the tube, to complete the filament heating circuit.

It will be realized that whereas I have described and shown a practical and operative 100 device, that nevertheless many changes might be made in the size, shape, number and disposition of parts without departing from the spirit of my invention. I therefore wish my drawings to be taken as in a broad 105 sense diagrammatic and illustrative rather than as limiting me to my specific description and showing.

The use and operation of my invention are 110 as follows:

I employ a mechanical rectifier including an insulated disc with two pairs of brushes or contacts or blades mounted about its periphery, the individual blades being spaced at 90° intervals. The motor is synchronized with the alternations of the current supply. In the operation of my device herein illustratively shown I may deliver a 220 volt alternating current to the auto transformer. The transformer may deliver an alternating current of say from 75 to 220 volts to the primary coil of the X-ray transformer. The secondary coil may deliver an alternating current of say from 30 to 100 kilovolts in the circuit including the brushes or blades B and B². The Coolidge tube is included in the circuit including the fixed blades B¹ B³. As the motor rotates in synchronism with the alternations of the current, a pulsating direct current of 30 to 100 kilovolts or more is passed through the Coolidge tube. Obviously these figures are merely illustrative. As the current passes across the gap between the fixed and the moving blades, the air, which is normally a good insulator, is ionized by the passage of the current, and becomes a good conductor to the extent that it is ionized. That is to say, the air across the gap is filled with free electrons, the atoms being broken up. The ionization of the air gap involves a definite energy loss and it is one purpose of my invention to minimize this loss by conserving the already ionized air. It is for this purpose that I associate with the air gaps or contacts dead air spaces or air reservoirs or chambers, namely the hollow spaces within the members B⁴, wherein the ionized air may gather. Thus the inevitable windage caused by the rapid rotation of the disc does not blow away or disperse the ionized air.

The result is an extremely efficient rectifier and a very small resistance or current loss at the brushes or gaps.

45 I claim:

1. In a line of current transmission including an air gap, opposed fixed and moving brushes, and means for holding about said air gap the air ionized by the passage of current thereacross, comprising a housing associated with the fixed brush, said fixed brush being mounted in the mouth of said housing, the housing enclosing a dead air space.
- 50 2. In a mechanical rectifier, a disc and means for rotating it, a plurality of brushes mounted on said disc and spaced about its periphery, a plurality of fixed brushes posi-

tioned about said disc, means for passing a current across said fixed and moving brushes, and means for holding about the air gaps between said fixed and moving brushes the air ionized by the passage of current thereacross.

3. In a mechanical rectifier, a disc and means for rotating it, a plurality of brushes mounted on said disc and spaced about its periphery, a plurality of fixed brushes positioned about said disc, means for passing a current across said fixed and moving brushes, and means for holding about the air gaps between said fixed and moving brushes the air ionized by the passage of current thereacross comprising housings associated with the fixed brushes.

4. In a mechanical rectifier, a disc and means for rotating it, a plurality of brushes mounted on said disc and spaced about its periphery, a plurality of fixed brushes positioned about said disc, means for passing a current across said fixed and moving brushes, and means for holding about the air gaps between said fixed and moving brushes the air ionized by the passage of current thereacross comprising housings associated with the fixed brushes, fixed brushes being mounted in the mouths of said housings, the housings enclosing each a dead air space.

5. In a rectifier which includes a plurality of lines of current transmission each formed by a plurality of relatively movable conductive members having an air gap therebetween, a rotor, a plurality of conductive members thereon, a plurality of fixed conductive members positioned about said rotor and in line with the conductive members on said rotor, and open mouthed housings, associated with each such fixed conductor, for holding about it the air ionized by the passage of current across the gap between the fixed and moving conductive members, the fixed members being in the form of blades, lying in the general plane of the rotor, and positioned within the housing mouths.

6. In a line of current transmission including an air gap, opposed fixed and moving brushes and means for holding about said air gap the air ionized by the passage of current thereacross, comprising a housing associated with the fixed brush, the housing enclosing a dead air space.

Signed at Chicago, county of Cook and State of Illinois, this 25th day of January, 1926.

WILLIAM G. HETTICH.
